UNITED STATES PATENT OFFICE.

JESSE A. L. HEFNER, OF DANESE, WEST VIRGINIA.

JAY BAR.

Application filed January 31, 1921. Serial No. 441,306.

To all whom it may concern:

Be it known that I, JESSE A. L. HEFNER, a citizen of the United States, residing at Danese, in the county of Fayette and State 5 of West Virginia, have invented new and useful Improvements in Jay Bars, of which the following is a specification.

This invention has reference to jay bars, and its object is to provide a device for use 10 in logging, whereby, in the event of the log running up on the horses or other means for dragging the log, the connection to the horses may be readily thrown off from the jay bar so that the horses may be drawn to 15 one side or the other of the log and released therefrom and given an opportunity to escape injury from the moving log.

The device is particularly useful in the wintertime when the ground may be slippery and where the log, in going down hill, 20 may gain momentum against which the horses can gain no control. The same is true where the ground is slippery from other causes. When the log, or string of 25 logs, starts to slide down hill, it is necessary to quickly disconnect the horses from the log in order to save the horses from injury, and the same would be true if a motor vehicle, such as a power truck, be used for a 30 like purpose.

The invention contemplates the employment of a bar for interposition in a chain between grabs to be driven one into the top 35 of the log and the other into the forward end thereof, so that the jay bar will lie upon the top of the log. Such bar has a top surface rounded between the side edges and rising from such top surface in approximately the center line of the bar is a hook-shaped projection of tapering, rounded contour, over which a spreader hook is engaged 40 and which hook is connected to the harness of the horses. In the event of the log starting on the horses and so endangering them, 45 the horses are drawn to one side or the other of the line of travel, whereupon the tapered form of the horn causes the hook to ride up and off the horn and so be discharged therefrom.

50 The invention will be best understood from a consideration of the following detailed description taken in connection with the accompanying drawing forming part of this specification, with the understanding, however, that the invention is not confined to 55 any strict conformity with the showing in

the drawing, but may be changed and modified so long as such changes and modifications mark no material departure from the salient features of the invention as expressed 60 in the appended claims.

In the drawing:

Fig. 1 is a perspective view of a log with the logging chain and jay bar secured thereto, and also showing a portion of the draw 65 chain.

Fig. 2 is a plan view of the jay bar.

Fig. 3 is a longitudinal section on the line 3—3 of Fig. 2.

Fig. 4 is a section on the line 4—4 of 70 Fig. 2.

Referring to the drawings, there is shown a jay bar A comprising an elongated plate-like body 1 of sufficient length, breadth and thickness for the purpose and provided with 75 a rounded or curved upper surface 2, and with ears 3 at opposite ends in about the longitudinal center line of the body member. The ears are each perforated as indicated at 4, for receiving chain links 5, each of which 80 is connected to a grab hook 6 of any appropriate form and which may be of a construction long in use.

Each ear 3 terminates at the outer end in a pointed or beveled extremity 7 so related 85 to the jay bar that when the latter is lying flat upon the log, the hook 7 will engage in the surface of the log either because of the pull on the jay bar or because of being driven more or less into the log.

Moreover, the body member 2 may be slightly curved on the under surface in the direction of its width, as indicated at 8 in Fig. 4. At about midway of the length of the body member 2, there is formed an 90 rising horn 9 of rounded, tapering contour, with the horn having a rising curve rearwardly of the line of draft and terminating in a blunt point 10.

Adapted to the hook 9 is an open link or hook 11 to embrace the horn 9 and fast to one end of a draft chain 12 to which the draft horses may be hitched. The rear one of the grab hooks 6 is driven at the appropriate point on the log into the latter, while 100 force applied to the horn 9 through the link 11 and chain 12 holds the rear grab hook 6 in proper position on the top of the log. The other grab hook is connected to the front eye 3 by means of links 13 and 14 and 105 a D link 15, which latter may be utilized for connecting the hook 11 when the log is 110

being drawn along a level or rising surface and where the log cannot move toward the horses.

When the hook 11 is applied to the horn 9, and the draft horses are pulling on the chain 12, the log indicated at B in Fig. 1 is drawn along the surface of the ground in the usual manner. If now, because of the nature of the surface over which the log is being hauled, the log tends to creep up on the horses, the latter, if properly trained or at word of command, will draw to one side of the line of travel of the log and the hook 11 being then no longer controlled by the overhanging hook 9 and because of the elliptical or other sectional shape of the hook, will ride up the latter and so pull loose from the hook, and consequently from the log, allowing the log, if it has sufficient momentum, to travel on past the horses without touching the latter or in any manner injuring them, and thus avoiding injury or even death to valuable stock. The jay bar and jay horn are in practice made in one piece and the upper surface of the jay bar is rounded transversely of its length so that there is nothing upon which the free end of the hook 11 may catch, so that the hook will readily slip from engagement with any part of the jay bar, wherefore the connection of the horses with the jay bar is automatically thrown off.

In practice, the jay bar may be approximately 7 inches in length and approximately 3 inches in width and 1 inch thick, with rounded or bevelled side edges. If the horn be about $1\frac{1}{4}$ inches high and about $1\frac{1}{2}$ inches in diameter at the base, such dimensions have proven effective in practice. The hook 11 is of a size to readily encircle the horn at the base of the horn, and consequently when the hook is turned to one side

or the other of the center line of draft, it will readily slip off from the horn, being prevented from catching on any part of the jay bar, because of the rounded contour of the upper surface of the bar, which presents rounded surfaces only to the hook so that the open part of the hook finds nothing upon which to hang.

What is claimed is:—

1. A jay bar for use in logging, comprising an elongated plate-like structure with a laterally rounded top surface and a transversely curved cylindrical under surface 55 adapted to fit the side of a log, and a horn rising from an intermediate point of the upper surface for receiving a chain hook, the jay bar being provided with ears at each end in the line of draft with each ear having 60 a downwardly-inclined tapered extremity terminating in a sharp point adapted to bite into the log.

2. A jay bar for use in logging, comprising a plate-like device with a round tapered 65 rearwardly-curved horn rising from an intermediate point of its length, and ears at the ends of the device in the line of draft with each ear having a downwardly-inclined tapered extremity, terminating in a sharp 70 point adapted to bite into the surface of the log to which the jay bar is applied.

3. A jay bar comprising an elongated plate-like structure with a laterally rounded upper surface, and a horn circular in cross 75 section rising from the upper surface intermediate the length thereof and inclined rearwardly and tapering toward its upper end, the rearward inclination of the horn increasing toward its extremity.

In testimony, that I claim the foregoing as my own, I have hereto affixed my signature.

JESSE A. L. HEFNER.
